CAR STOP

Sam W. Cortese, Dragerton, Utah, assignor to United States Steel Corporation, a corporation of New Jersey

Application February 16, 1956, Serial No. 565,927

7 Claims. (Cl. 104—257)

The present invention relates to an improved car stop adapted to be installed on a rail of a trackway for halting the movement of rail cars or other rolling stock therealong. The device of the invention is especially suitable for use on mine trackways where it is necessary to position rail cars on the trackway at desired points for loading and unloading particularly where the trackway runs along a grade.

It is an object of the present invention to provide an improved car stop which is of simple, rugged and inexpensive construction and which may be easily installed on a rail of a trackway.

It is another object of the present invention to provide an improved car stop which after installation on a rail of a trackway is capable of being moved, by simple manual manipulation, from an operative stopping position engageable by a car wheel to an inoperative position clear of the rail to permit unobstructed movement of rolling stock along the trackway.

It is a further object of the present invention to provide an improved car stop of the character described which is provided with automatic latching means for positively locking the car stop in operative position.

These and other objects will become more apparent after referring to the following specification and attached drawings, in which:

Figure 1 is a view in perspective;

Figure 2 is an end view;

Figure 3 is a side elevational view looking toward the outer side of the rail on which the stop of the invention is installed;

Figure 4 is a view similar to Figure 3 looking toward the inner side of the rail;

Figure 5 is a cross sectional view taken on the line V—V of Figure 4; and

Figure 6 is an end view showing the stop of the invention in inoperative position clear of the rail.

Referring more particularly to the drawings, reference numeral 2 designates a base block having spaced end walls 4 connected together by an angle plate 6 clamped against the bottom of the base flange of a rail R between a pair of supporting ties T. It will be noted that for purposes of this description the side of the rail R toward the ends of the ties is referred to as its outer side while the opposite side of the rail, that is, the side remote from the ends of the ties, is referred to as its inner side. When the base block 2 is clamped into position under the rail R, in the manner to be described, the end walls 4 extend in a plane normal to the longitudinal axis of the rail, as best shown in Figure 5. The base block 2 extends under the base flange of the rail R with the end walls 4 and the angle plate 6 projecting outwardly beyond the outer side of the rail. A housing 8 having spaced side walls 10 is fitted over the base block 2 with its side walls 10 closely adjacent the end walls 4 of the base block. A vertical cheek plate 12 is disposed on each side of the housing 8 closely adjacent the side walls 10. The cheek plates are fastened to the

2

ties T by means of lateral flanges 14 attached thereto and extending in a horizontal plane therefrom overlying the top surfaces of the ties. The flanges are spiked to the ties adjacent the outer edge of the base flange of the rail. The bottom portions of the cheek plates extend across the bottom of the rail R. As shown in Figure 4, an edge 4a of each of the end walls 4 extends vertically under the inner side of the rail R. Each edge 4a may be joined to the corresponding edge 12a of the cheek plate 12 adjacent thereto by means of a small plate 16 welded to the bottom portions of each pair of adjacent edges 4a and 12a. The housing 8 is provided with a stop member 20 which projects upwardly from the top of the rail R when the device is in operative position as will be more fully explained hereinafter.

The housing 8 is pivotally connected with the base block 2 and cheek plates 12 by means of two hinge pins 18 which are fitted through suitable aligned openings in the adjacent cheek plates 12, side walls 10 and end walls 4 on each side of the housing 8. The hinge pins 18 are co-axially disposed under the rail R.

Each of the edges 4a of the end walls 4 is provided on its upper portion with a threaded stud 22 which extends normal to the hinge pins 18 and projects from under the inner side of the rail. The edge 12a of each of the cheek plates 12 is provided with a similar stud 24 which extends parallel with stud 22 on the adjacent end wall edge 4a. A rail clamp 28 is fitted over each pair of studs 22 and 24 in clamping position on the base flange of the rail R. The rail clamps 28 are held in position by means of lock nuts 30. A rail hook clamp 32 which engages the base flange of the rail R is welded or otherwise rigidly mounted on the upper surface of each of the end walls 4 and aids in clamping the base block securely onto the rail.

Each of the side walls 10 is provided with an elongated slot 34 from which projects the ends of a horizontal bar 36 mounted within the housing 8 parallel with and above the longitudinal axis of the base block 2. Each of the cheek plates 12 is provided with a transverse groove or slot 38 in the upper portion thereof for receiving the projecting ends of the bar 36 when the device is in operating position as best shown in Figures 1 and 2. A stem 40 is welded or otherwise attached to the bar 36 intermediate its ends. The stem 40 extends from the bar 36 and projects outwardly and upwardly of the housing through a nipple or socket 42 which is integral with and surrounds an opening in the upper wall of the housing. A helical compression spring 44 is mounted around the stem 40 with one end bearing against the bar 36 and its other end bearing against the inner surface of the top of the nipple 42. The spring 44 serves to constantly urge the bar 36 away from the nipple 42 and thus positively lock the bar in position with its ends engaged in the slots 38 when the housing 8 is in operative position. The stem 40 is manipulated manually to lift the bar 36 against the pressure of the spring 44. The stem 40 has a handle 41 attached to its upper end to facilitate manipulation thereof. If desired, a guide bracket 43 having a hole therein may be attached to the outer face of the stop member 20 for guiding the vertical movement of the stem 40.

The stop member 20 is preferably fabricated from two plates welded together, as is shown in Figure 5. The plate making up the outer side of the stop member 20 is provided with an extending angular portion 46 on the bottom thereof which fits against the side of the rail when the device is in operative position. The extending portion 46 tends to limit the pivotal movement of the housing so as to insure proper positioning of the stop member 20 when the housing 8 is pivoted into operative position on the hinges 18.

In normal operating position the bar 36 has its ends fitted in the slots 38 and the stop member 20 projects vertically upward of the rail R so as to be engageable by the wheel of a rail car traveling on the rail. When it is desired to place the device in inoperative position clear of the rail R the handle 41 is grasped and the stem 40 is pulled upwardly to raise the bar 36 and lift its ends out of slots 38. The housing 8 is then pivoted downwardly on the pins 18 so that the stop member 20 extends outwardly from the rail R as shown in Figure 6. When the stop member is in this position the wheels of a car or other rolling stock may travel over the rail R unimpeded. Each of the cheek plates 12 is provided with an arcuate edge 48 on which the ends of the bar 36 ride as the housing 8 is pivoted on the hinge pins 18. A shoulder abutment 50 may be provided on the bottom of each of the arcuate edges 48 for limiting the downward movement of bar 36, as shown in Figure 6. To return the car stop to operative or "up" position, stop member 20 is raised toward the rail until the extension 46 engages the outer side of the rail. When the stop member reaches this position the spring 44 exerting pressure on bar 36 forces it downwardly so that its ends are engaged in the slots 38 and the device is thus automatically locked in position.

While one embodiment of my invention has been shown and described, it will be apparent that other adaptations and modifications may be made without departing from the scope of the following claims.

I claim:

1. A stop for halting the movement of a railroad car along a track rail supported on spaced ties which comprises a base block adapted to be clamped against the bottom of the base flanges of said rail between two adjacent ties, said block including a plate extending along the bottom of said base flanges and spaced end walls extending upwardly and normal to the longitudinal axis of said plate and normal to said rail when said base block is clamped against said base flanges, said end walls having clamping means for clamping said base block to said base flanges, a shaft extending through said side walls directly below said base flanges and parallel with the longitudinal center line of said rail when the base block is clamped against said base flanges, a housing fitting over said block and journaled on said shaft for tilting toward and away from said rail, said housing including spaced side walls disposed closely adjacent said end

walls, a stop plate carried by said housing so as to stand vertically on top of the rail in one position of the housing when said base block is clamped against said base flanges, and manually releasable locking means effective to hold said housing in said one position.

5. A stop for rail cars as defined by claim 1 in which said clamping means includes clamping studs mounted on said end walls, said clamping studs extending normal to said shaft and projecting outwardly from under the bottom of the base flanges of the rail on one side thereof when said base block is clamped against said base flanges.

10 10. A stop for rail cars as defined by claim 2 in which said base block has hooks thereon in alignment with said studs to engage the base flange of the rail on the side thereof opposite said one side.

15 15. A stop for rail cars as defined by claim 1 in which said manually releasable locking means includes a bar extending through said housing normal to said side walls and parallel with said shaft, the side walls of said housing having slots therein for receiving said bar, the ends of said bar extending through said slots, a cheek plate closely adjacent each of said side walls on the side thereof away from said housing, and means carried by said cheek plates for mounting said cheek plates one on each 20 20. 25 of said adjacent ties, each cheek plate having a notch therein for receiving an end of said bar when said housing is in said one position.

25 25. A stop for rail cars as defined by claim 4 in which said cheek plates have arcuate edges on which the ends 30 30. of said bar ride as the housing is tilted on said shaft.

30 30. 35. A stop for rail cars as defined by claim 4 in which said bar has an operating stem normal thereto and said housing has an opening through which said stem extends so as to be accessible on the exterior thereof.

35 35. 35. 7. A stop for rail cars as defined by claim 6 in which said housing has a socket overlying said opening, and a compression spring seated thereon tending to urge said bar into said notches.
